(57) **CLAIM**

The ornamental design for a water distribution box, as shown and described.

DESCRIPTION

FIG. 1 is a front perspective view a water distribution box showing our new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

The broken lines showing various elements of the water distribution box are included for the purpose of illustrating non-claimed subject matter and form no part of the claimed design.
